UNITED STATES PATENT OFFICE.

CHARLES BENNETT, OF RICHMOND HILL, NEW YORK.

DRAWING INSTRUMENT.

Application filed October 27, 1925. Serial No. 65,159.

This invention relates to drawing instruments and more particularly to pens forming parts thereof. It is adapted for use both in right-line pens and compass pens as well 5 as bow pens.

In pens of this general character it is the common practice to construct them with two blades, either one or both of which are flexible and with said blades co-operates an adjustment screw working loosely through a perforation in one and threaded through the other. The tensioning of the flexible blade is such that said blades normally tend to separate at their free ends and by adjustment of 10 the screw the free or working ends of the pen are brought into the desired proximity to produce the adjustment necessary for the line of the desired width. In all drawing instruments employing pens of which I am 15 aware, the foregoing principle of adjustment through the utilization of the adjusting screw has been the universal practice. In spite of the general usage of this construction, however, it is open to many disadvantages among which may be mentioned the 20 all too frequent stripping of threads of the adjusting screw or the tapped hole in which it operates, the losing of said screw and frequently the inability to properly replace the 25 lost adjusting screw by a new one due to the wide variety of threads and screw sizes employed in the great number of pens found on the market.

With the foregoing considerations in 30 mind, the primary objects of the present invention are to provide a greatly simplified adjustment for drawing pens, compasses and bow compasses which will be economical to manufacture, durable and thoroughly efficient in use.

Speaking generally, the present invention utilizes for the purpose of adjustment between the working points or ends of the blades, co-operating cam members mounted 45 on the respective blades and normally maintained in contact with one another by suitable resilient means normally overcoming the tendency of the blades to spring apart. At least one of the cam members is supported 50 on its associated blade for rotation and is provided with a finger piece which, when turned, exerts a cam action upon the co-operating cam of the other blade for the purpose of effecting relative movement between 55 the free ends of the blade and in so doing produces that adjustment which, within the

judgment of the draftsman, will produce the line of the desired width. In one of its preferred practical forms, the pen is made with a rigid blade and a relatively resilient 60 blade, the two blades being associated in such manner that the latter will normally tend to retract or spring away from the rigid blade. On the flexible blade is mounted a spring which is manually movable into 65 the position to overcome the inherent resiliency of the blade and force the free end of said blade into contact with the corresponding end of the rigid blade. On either one of the blades, preferably the flexible blade, is 70 mounted a fixed mandrel and in axial alignment therewith there is mounted on the rigid blade a suitable spindle carrying between the two blades a cam and on the exterior of the rigid blade a suitable finger piece. The 75 face of the cam as well as the face of the mandrel are complementarily cam shaped and through the action of the spring to which I have referred these cam faces are maintained at all times in abutting relation. It therefore follows that the cam may 80 be caused to revolve over the fixed face of the mandrel and in so doing effect the adjustment desired. In practice there is sufficient friction between the cam, its spindle and the 85 rigid blade to maintain the cam against inadvertently shifting from any position in which it is manually placed and thus the parts are, by this friction, or otherwise, maintained in adjustment. The general 90 structure outlined is that applied particularly to bow pens but I am aware that it is equally adaptable to other drawing instruments such as compasses, bow compasses, etc.

Features of the invention other than those 95 specified, as well as advantages thereof, will be apparent in the following detailed description and from the accompanying drawings and appended claims.

In the accompanying drawings, I have 100 illustrated different practical embodiments of the present invention, but I wish it understood that these showings are for the purpose of illustration only and do not define the limits of the invention.

In said drawings:

Figure 1 is a face view of a right-line pen embodying the present invention.

Figure 2 shows the pen illustrated in Figure 1 partly in elevation and partly in 110 section on the line 2-2 of Figure 1.

Figure 3 is another view of the same pen

and showing same as it appears on the side opposite that shown in Figure 1.

Figure 4 is the side elevation of the pen showing blades in relatively open position, 5 as for cleaning or sharpening.

Figure 5 is a view similar to Figure 3 but showing the pen in the condition in which it is illustrated in Figure 4.

Figure 6 illustrates the invention as applied to a bow compass and also showing a slightly modified form of the invention.

Referring to the drawings, and more particularly to the Figures 1 to 5 inclusive thereof, the right-line or bow pen as illustrated embodies a suitable handle 1 at one end of which is mounted a rigid blade 2 and a relatively flexible blade 3. It will be apparent from Figure 2 that the blade 2 is relatively rigid and is mounted rigidly 20 on the handle 1. Blade 3, in contra-distinction, while mounted rigidly at its base on the handle, is provided intermediate its ends with a portion 4 of reduced cross section which imparts to this blade its resilient 25 characteristics. The parts are so organized that the flexible blade 3 will normally spring away or retract from the rigid blade 2 and partake of the position shown in Figure 4.

Mounted either on the handle 1 or at the 30 base of the blade 3 is a spring 5 shown as a leaf spring. This spring 5 is mounted on the pin 6 for pivotal movement and is adapted to be moved from the retracted position of Figures 4 and 5, wherein it is 35 disengaged from that portion of the blade 3 beyond the spring section 4, into the position of Figures 2 and 3, wherein it will bear upon the flexible blade 3 at the point between the spring section 4 and the free end 40 of the flexible blade. In order to maintain the spring 5 from inadvertently shifting from this position into which it is adapted to be manually moved, said spring preferably has a protuberance 7 on its inner face and this protuberance is adapted to seat within the depression 8 formed on the top of the face of the blade 3. In practice, the protuberance 7 may be formed by punching out a projection from the body of the spring 50 or by bending the spring or by placing a suitable protruding member thereon.

In any event, the spring 5 is made sufficiently heavy to overcome the tendency of the blade 3 to retract from the blade 2 and 55 consequently such spring 5 tends at all times to force the free end of the blade 3 into contact with the free end of the blade 2 as clearly shown in Figure 2. Mounted on the blade 3 in rigid relation thereto is a 60 suitable mandril 9 and mounted upon the blade 2 co-axial with the mandril 9 is a spindle 10. This spindle is rotatably mounted on the blade 2 and carries at its inner end a head 11, and at its outer end said 65 spindle is provided with a finger piece 12.

The face of the head 11 abuts the contiguous face of the mandril 9 and these two faces, designated, respectively, 11^a and 9^a, (see Figure 4) are in the form of cam surfaces, i. e. are preferably cut on the slant. Accordingly, rotation of the piece 12 will cause the cam surface 11^a to rotate over the sloping surface 9^a of the fixed mandril 9 and in so doing the flexible blade 3 will be caused to move toward or away from the blade 2 for the purpose of obtaining the desired adjustment. The finger piece 12 is knurled to afford a finger grip and to allow it to be made relatively small while still permitting it to be properly grasped.

The construction illustrated in Figure 6 operates in substantially the same manner as that described in connection with Figures 1 to 5, but for the purpose of illustration the construction of Figure 6 is shown as associated with a bow compass. It differs structurally from the showing of Figures 1 to 5 mainly in the fact that the operating rotary cam, instead of being positioned exteriorly of the rigid blade is positioned intermediate the mandril 9 and said blade, and the spindle 10 is passed through a perforation in the blade provided at its outer end with a fixed collar forming the stop 14. The leaf spring 15 riveted to the rigid blade 2 bears against the stop 14 and impels the stem of the spindle in an outward direction to bring the face of the finger piece tightly against the inner face of the rigid blade in order to increase the friction between these parts, whereby there will be less liability of inadvertent shifting of the cam member 9 after it has been placed in the desired adjustment. In this connection it may be noted, from the structural standpoint, that the friction producing spring 15 may be either bifurcated to straddle the spindle and bear against the stop 14 or said spring may be perforated so that the spindle passes through such perforation with the stop exterior of the spring. In either event the mode of operation is the same.

I wish it understood, in this connection, that the pen structure illustrated in Figure 6 including a spring for the augmenting of friction, may be applied if desired to right-line pens of the character shown in Figures 1 to 5 and, conversely, bow compasses may be made with pen parts constructed in the same manner as illustrated in Figures 1 to 5. In other words, the two distinct forms of the invention illustrated may be used interchangeably in pens, compasses or other instruments.

The compass construction illustrated in Figure 6 is conventional, that is to say the bow portion of the compass with its adjusting nut, handle and needle point is made as heretofore.

It will be apparent from the foregoing de-

tailed description that this invention embodies many novel peculiarities that it is unusually simple in construction and economical to manufacture, and that it is far more durable than the threaded adjustments heretofore commonly employed. In practice, the cam faces 9^a and 11^a are made with a relatively slight pitch and are not abrupt in their operation but, in contra-distinction, will, when the finger piece is rotated, function with very fine adjustment and in a perfectly smooth manner. It will, of course, be understood that when it is desired to clean or sharpen the pen the leaf spring 5 can be readily swung from its normal position in Figures 2 and 3 to its inactive position in Figures 4 and 5 in order that the inherent resiliency of the flexible blade 3 may automatically act to move it into the position of Figure 4. After the cleaning or sharpening operation, the parts may be returned to the co-operative relation of Figure 2 by simply pressing the blades together manually and moving the spring 5 into the position of Figure 2, whereupon the parts will return to the adjustment which they previously occupied. It is of practical importance that the present invention may be readily associated with or applied to pens previously employing the screw adjustment by discarding the adjusting screw and applying parts of the present invention thereto.

The foregoing detailed description sets forth the invention in its preferred practical form, but the invention is to be understood as fully commensurate with the appended claims.

Having described my invention, what I claim as new and desire to secure by Letters Patent is:

1. A drawing instrument embodying a pair of co-operating blades which are relatively movable with respect to one another, means for normally impelling the free ends of the blades toward one another, and manually operable cam means for spacing the free ends of said blades the desired distance apart.

2. A drawing instrument embodying a pair of co-operating blades one of which is relatively rigid and the other of which is relatively flexible, the flexible blade being tensioned to normally tend to spring away from the rigid blade, a spring co-operating with the flexible blade to force it against its inherent tension in the direction of the rigid blade, and manually operable cam means for regulating the spacing between the free ends of said blades.

3. A drawing instrument embodying a pair of blades one of which is relatively rigid and the other of which is relatively flexible and is tensioned to normally tend to spring away from the rigid blade, a leaf spring pivotally mounted on the instrument

and normally occupying a position to exert tension on the flexible blade and force it in the direction of the rigid blade, and manually operable cam means for regulating the space between the free ends of said blades, 70 said spring being movable into a position to permit the flexible blade to automatically move into a remote position with respect to the rigid blade.

4. A drawing instrument embodying a 75 pair of blades one of which is relatively rigid and the other of which is relatively flexible, means for normally impelling the flexible blade into position wherein its free end will engage the free end of the rigid blade, a mandril carried by one of said blades, and a manually operable cam carried by the other blade and engaging the mandril, the contacting portions of the manually operable member and the mandril being 80 of cam like formation whereby the rotation of the manually operable member will effect adjustment in the spacing of the free ends of the blades.

5. A drawing instrument embodying a 90 pair of blades one of which is relatively rigid and the other of which is relatively flexible, means for normally impelling the flexible blade into position wherein its free end will engage the free end of the rigid blade, a mandril carried by one of said blades, a manually operable cam carried by the other blade and engaging the mandril, the contact portions of the manually operable member and the mandril being 95 of cam like formation whereby the rotation of the manually operable member will effect adjustment in the spacing of the free ends of the blades, and means for frictionally maintaining the manually operable member 100 against inadvertent movement.

6. A drawing instrument embodying a relatively rigid blade, a relatively flexible blade tensioned to normally tend to spring away from the rigid blade, a leaf spring 110 pivotally mounted on the instrument and having a protuberance adapted to engage with the depression in the flexible blade, said spring being of sufficient strength to force the flexible blade in the direction of the rigid blade, a mandril rigidly carried by one of the blades, a spindle rotatable in the other blade and aligned with respect to the mandril, a head carried by the spindle and engaging with the mandril, a finger piece 115 also carried by the spindle for operating same, and the contacting faces of the head and mandril being sloping, whereby the head may be rotated for the purpose of regulating the spacing between the free ends 120 of the blades.

Signed at Brooklyn, New York, in the county of Kings and State of New York this 17th day of October A. D. 1925.

CHARLES BENNETT.
